UNITED STATES PATENT OFFICE.

BERNHARD TROSKY, OF BROOKLYN, NEW YORK.

RAZOR-STROPPER.

1,262,412.

Specification of Letters Patent. Patented Apr. 9, 1918.

Application filed February 23, 1917. Serial No. 150,568.

To all whom it may concern:

Be it known that I, BERNHARD TROSKY, a citizen of the United States, and a resident of the city of New York, borough of Brooklyn, in the county of Kings and State of New York, have invented a new and Improved Razor-Stropper, of which the following is a full, clear, and exact description.

10 This invention relates to razor stropers and has to deal particularly with improvements in stropers of that type disclosed in United States Letters Patent Number 1,213,556, granted to me on the 23rd day of

15 January, 1917.

The invention has for its general objects to improve the construction of the blade-holding means whereby safety razor blades of various sizes, shapes and designs can be 20 effectively held in proper position for coaction with the stropping rolls or elements.

A more specific object of the invention is the provision of a blade-holding device which embodies a plurality of blade-clamping hooks, one or both of which are movably mounted, and the hooks are normally urged toward each other by spring means, whereby the hooks will firmly grip a blade, the said hooks being mounted on a support 25 which is in permanent coöperative relation with the stropping rolls.

Still another object of the invention is the provision of blade-engaging lugs or stops which coöperate with the hooks to 30 more firmly hold certain types of blades.

With such objects in view, and others which will appear as the description proceeds, the invention comprises various novel features of construction and arrangement of 40 parts which will be set forth with particularity in the following description and claims appended hereto.

In the accompanying drawing, which 45 illustrates one embodiment of the invention and wherein similar characters of reference indicate corresponding parts in all the views,

Figure 1 is a horizontal section of the stropper on the line 1—1, Fig. 3, with portions of the blade-holding means in section; 50 Fig. 2 is a bottom plan view of the blade-holding means;

Fig. 3 is a transverse section on the line 3—3, Fig. 1;

Fig. 4 is a sectional view on the line 4—4, 55 Fig. 1;

Fig. 5 is a sectional view on the line 5—5, Fig. 1;

Fig. 6 is a fragmentary sectional view similar to Fig. 3, showing a Gillette blade clamped in the holder; 60

Fig. 7 is a sectional view on the line 7—7, Fig. 1;

Fig. 8 is a perspective view of the spring anchoring and hook-holding plate; and

Fig. 9 is a perspective view of one of the 65 blade-gripping hooks.

Referring to the drawing, A designates the casing of the stropper, which, in the present instance, is shown of upper and lower sections 1 and 2 hingedly connected 70 together at a, and each section has a frame B, the end plates 3 of which carry rotatable alternately-acting stropping elements C. These elements are connected together by gears 4, and on one of the elements is an 75 operating crank 5.

The frame B in the lower section has a horizontal plate or bar 6 which is adapted to support a blade in coöperative relation with the stropping elements C, and if desired the frame B in the upper section may have a matching plate or bar 7 to grip the top of the blade resting on the lower plate 6, as shown in Figs. 3 and 6, wherein the blades are designated D and E, respectively. 80 The bars 6 and 7 have longitudinal portions 8 and 9 relatively disposed so that one portion is out of the plane of the other. In other words, the portions 9 are spaced farther apart than the portions 8 when the 85 stropper casing is closed, as in Fig. 3, and between the portions 9 the enlarged space accommodates the reinforcing backing d of the blade D. By arranging the portions 8 and 9 of each blade-engaging plate in different levels a longitudinal shoulder 10 is provided so as to facilitate the proper positioning of the blade D. 95

A pair of oppositely disposed blade-gripping hooks 11 and 12 are associated with 100 the portion 8 of the lower plate 6. Each hook comprises a flat body 13, and on one end thereof is a bent-back member forming the bill 14. The bodies 13 lie under the portion 8 of the plate 6, such plate having recesses 15 through which the bills of the hooks project upwardly. The body portions of the hooks are supported in position by a supporting plate 16 constructed as shown in Fig. 8 and having apertures 17 into which 110

are engaged lugs 18 stamped out from the portion 9 of the blade-supporting plate 6. The hooks 11 and 12 are slideable toward and from each other so as to accommodate themselves to blades of different lengths. Suitable spring means are employed to hold the hooks yieldingly toward each other. For this purpose a helical spring 19 is connected with the body 13 of the hook 12, there being lugs 20 and 21 on the hook 12 and plate 16, respectively. A second helical spring 22 has its ends connected with lugs 23 and 24 on the plate 16 and hook 11, respectively. When the hooks 11 and 12 are spread apart the springs are extended, and when the hooks are released they move toward each other. For short blades only one hook, say the hook 12, must be moved outwardly so as to permit a blade to be inserted, one end of the blade being placed under the hook 11, and with the blade resting on the plate 6, the hook 12 is released and its spring causes the said hook to move inwardly and grip the blade. For long blades, as the Gillette blade E, indicated by dotted lines, Fig. 1, both hooks 11 and 12 are extended. To facilitate the insertion of the blade the hook 12 is capable of being held in its outermost position by means of a catch 25, Figs. 4 and 7, which is adapted to be engaged in a recess 26 in the bottom of the hook 12, the hook 12 having a slight resiliency so as to permit the hook to be engaged with or disengaged from the catch 25. As shown in Figs. 3 and 6, the bodies 13 of the hooks are confined between the edge of the portion 9 of the plate 6 and the depending flange 27 on the same plate. The outer corners of the lower plate 6 have upstanding lugs 28 which coöperate with the hooks 11 and 12 for holding steady a Gillette blade, as shown in Fig. 1. To facilitate the insertion and removal of a blade, the plate 6 has a central recess 29 cut in its front edge, and the adjacent wall 30 of the casing has a recess 31 for the same purpose. To properly position the blade a finger or indicator 32 is formed on one wall of the casing, as shown in Fig. 1, and the inner edge of the blade is brought into alinement with this indicator so that the said inner edge of the blade will be in stropping relation to the stropping element. From the foregoing description taken in connection with the accompanying drawing, the advantages of the construction and method of operation will be readily understood by those skilled in the art to which the invention appertains, and while I have described the principle of operation, together with the device which I now consider to be

the best embodiment thereof, I desire to have it understood that the device shown is merely illustrative and that such changes may be made when desired as fall within the scope of the appended claims. 65

Having thus described my invention, I claim as new and desire to secure by Letters Patent:

1. A stropper comprising a supporting structure, stropping means thereon, a plate for supporting a blade, relatively movable hooks associated with the plate for gripping the ends of the blade, and fixed members associated with the plate for engaging the ends of the blade. 75

2. A stropper comprising a supporting structure, stropping means thereon, a plate for supporting a blade, relatively movable hooks associated with the plate for gripping the ends of the blade, and fixed members associated with the plate for engaging the ends of the blade, said hooks being disposed to engage the blade at points between the edge being sharpened and the outer corners of the blade. 80

3. A stropper comprising a supporting structure composed of relatively movable sections, coacting stropping means mounted in the respective sections, plates on the sections for gripping opposite sides of a blade, relatively movable hooks on one of the plates for gripping the ends of the blade, and means for moving the hooks toward each other. 85

4. A stropper including stropping elements, a pair of relatively movable blade-gripping hooks, spring means for urging the hooks toward each other, and a catch with which one of the hooks releasably engages for holding the hooks separated for receiving between them the blade to be sharpened. 95

5. A stropper including a supporting structure, stropping means thereon, a blade-holding plate having different portions on different levels, a second plate fastened to the first-mentioned plate, blade-gripping hooks disposed with their bodies between the second-mentioned plate and one of the portions of the first-mentioned plate, and spring means urging the hooks toward each other. 105

6. A stropper comprising a supporting structure, stropping means therein, a pair of plates fastened together, and movable means held between the plates and having portions bent into hook bills projecting from the plates to grip the ends of a blade resting on one of the plates. 115

BERNHARD TROSKY.
